(57) **CLAIM**

The ornamental design for an inverter housing, as shown and
described.

DESCRIPTION

FIG. 1 is a perspective view of an inverter housing showing
the new design;

FIG. 2 is a front view of the inverter housing shown in FIG.
1;

FIG. 3 is a back view of the inverter housing shown in FIG.
1;

FIG. 4 is a right side view of the inverter housing shown in
FIG. 1;

FIG. 5 is a left side view of the inverter housing shown in
FIG. 1;

FIG. 6 is a top view of the inverter housing shown in FIG.
1; and,

FIG. 7 is a bottom view of the inverter housing shown in
FIG. 1.

The broken lines depict portions of the inverter housing
which form no part of the claimed design.
